(57) **CLAIM**

The ornamental design for a flow conditioner, as shown and described.

DESCRIPTION

FIG. 1 illustrates a front perspective view of a flow conditioner having integral vanes on both sides of the flow conditioner at least partly following contours of an outer ring of holes or apertures.

FIG. 2 illustrates a rear perspective view of a flow conditioner of FIG. 1.

FIG. 3 illustrates a front view of the flow conditioner of FIG. 1.

FIG. 4 illustrates a rear view of the flow conditioner of FIG. 1.

FIG. 5 illustrates a side view of the flow conditioner of FIG. 1.

FIG. 6 illustrates a rear perspective view of a flow conditioner having integral vanes on a downstream side of the flow conditioner at least partly following contours of an outer ring of holes or apertures according to another embodiment of the invention.

FIG. 7 illustrates a front perspective view of a flow conditioner of FIG. 6.

FIG. 8 illustrates a front view of the flow conditioner of FIG. 6.

FIG. 9 illustrates a rear view of the flow conditioner of FIG. 6.

FIG. 10 illustrates a side view of the flow conditioner of FIG. 6.

FIG. 11 illustrates a rear perspective view of a flow conditioner having integral vanes on a downstream side of the flow conditioner at least partly following contours of an inner ring and an outer ring of holes or apertures according to another embodiment of the present invention.

FIG. 12 illustrates a front perspective view of a flow conditioner of FIG. 11.

FIG. 13 illustrates a front view of the flow conditioner of FIG. 11.

FIG. 14 illustrates a rear view of the flow conditioner of FIG. 11.

FIG. 15 illustrates a side view of the flow conditioner of FIG. 11.

FIG. 16 illustrates a rear perspective view of a flow conditioner having integral vanes on an upstream side of a flow conditioner at least partly following contours of an outer ring of holes or apertures according to another embodiment of the present invention.

FIG. 17 illustrates a front perspective view of a flow conditioner of FIG. 16.

FIG. 18 illustrates a front view of the flow conditioner of FIG. 16.

FIG. 19 illustrates a rear view of the flow conditioner of FIG. 16; and,

FIG. 20 illustrates a side view of the flow conditioner of FIG. 16.
